[57] CLAIM

The ornamental design for a traffic barricade, as shown and described.

DESCRIPTION

FIG. 1 is a front perspective view of a traffic barricade embodying our new design, with the broken line showing for illustrative purposes only and forming no part of the claimed design;

FIG. 2 is a back perspective view thereof;

FIG. 3 is a back view thereof;

FIG. 4 is a side view thereof;

FIG. 5 is a top view thereof;

FIG. 6 is a front view thereof;

FIG. 7 is a bottom view thereof;

FIG. 8 is a perspective front view of an alternate embodiment thereof; and,

FIG. 9 is a perspective back view of an alternate embodiment thereof.
